UNITED STATES PATENT OFFICE.

HAZARD BARDIN, OF OKAHUMPKA, FLORIDA.

TENT-COVERING.

1,283,452.

Specification of Letters Patent.

Patented Nov. 5, 1918.

Application filed October 9, 1917. Serial No. 195,557.

To all whom it may concern:

Be it known that I, HAZARD BARDIN, a citizen of the United States, residing at Okahumpka, in the county of Lake and State of Florida, have invented certain new and useful Improvements in Tent-Coverings; and I do hereby declare the following to be a full, clear, and exact description of the invention, such as will enable others skilled in the art to which it appertains to make and use the same.

My invention relates to tent coverings, and more particularly to devices of this nature for protecting trees, shrubbery, plants and like vegetation from frost, chilly winds or the hot rays of the sun as the case may be.

One of the objects of this invention is to provide novel tent coverings constructed in a manner for efficiently protecting the vegetation whether the same be planted in rows 20 or in hills and which coverings can be positioned and secured at their edges to the ground to cover the plants or removed therefrom in a speedy and ready manner.

These and other objects and advantages will more fully appear as the nature of the invention is more clearly understood from the following description taken in connection with the accompanying drawings wherein 25 there is disclosed certain embodiments of the invention, but which are susceptible to numerous alterations and variations in the form, construction and arrangement of the parts to meet the exigencies of the case without departing from the spirit of the invention or exceeding the scope of the claim.

In the drawings:

Figure 1 is a perspective view of one form of the invention for covering vegetation 40 that is planted in rows.

Fig. 2 is a vertical transverse sectional view, drawn on an enlarged scale.

Fig. 3 is a detail perspective view of one of the corners of the covering, drawn on an 45 enlarged scale, showing the means for securing the corners of the covering to the ground.

Referring to Figs. 1, 2 and 3 of the drawings, 1 indicates the tent covering, which may be formed of any suitable cheap fabric, 50 and in this instance the fabric is formed in elongated rectangular sheets and has secured therein along its longitudinal medial line by the row of stitches 2 the cord 3 which projects for a suitable distance beyond the ends 55 of the covering 1 and adapted to be drawn taut and its ends suitably secured to the

upper end portions of the stakes or rods 4 which are driven into the ground at the ends of the covering and extend a sufficient height above the ground to enable the covering 1 to be positioned over the plants and out of contact therewith. The side edges of the covering 1 are hemmed or otherwise suitably reinforced as at 5, and suitably secured upon the corners of the covering 1 are 60 the loops 6 which pass through the eyes 7 of the corner pins 8. Also upon the side edges of the covering 1 between the respective corners are the plurality of loops 9 for engaging the eyes 10 of the side pins 11. 65

After the covering 1 has been suspended upon the stakes 4 through the medium of the cord 3, the side edges of the covering are each moved outwardly from the sides of the plants and the corner pins 8 and side 70 pins 11 are driven into the ground, preferably at an inclination as shown in Fig. 2, for securing the edges of the covering 1 to the ground. 75

The foregoing construction is primarily 80 designed for covering vegetation that is planted in rows and the covering may be of any suitable length and width in accordance with the character of plants to be covered, and any number may be employed for 85 covering the row by positioning the coverings end to end.

The devices are capable of being readily applied to or readily removed from the rows of plants or the like and are primarily 90 designed for protecting the plants from the danger of frost and chilly winds and may also be employed for protecting the plants from the scorching rays of the sun. The covering may be positioned over the plants 95 at night when there is danger of frost and removed the next morning if desired, however, in certain cases the corner and side pins at the side of the covering facing the sun may be withdrawn from the ground and this half of the cover thrown backwardly over the cord 3 or upon the other side of the covering and thereby expose the plants to the rays of the sun at one side and protecting the plants from chilly winds at the 100 other side of the plants, and at night, if there is danger of the plants becoming frozen or frost bitten, the side which has been folded back during the day may be replaced for entirely protecting the plants 105 at night. 110

Having described my invention, what I

claim as new and desire to secure by Letters Patent, is:—

In a device of the character specified, the combination of an elongated fabric body, 5 said fabric body being stitched along its longitudinal medial line to provide a tubular portion thereat, a cable extending through said tubular portion and projecting for a distance beyond the ends of said body portion, stakes disposed at the ends of said body portion for receiving the projecting ends of said cable, a plurality of loops secured upon the side edges of said body, a

plurality of pins, and ring-shaped heads upon said pins secured upon said loops, 15 whereby to secure the side edges of said body to the ground in spaced relation to each other when said pins are driven into the ground.

In testimony whereof I have signed my 20 name to this specification in the presence of two subscribing witnesses.

HAZARD BARDIN.
